US00D972647S

(12) **United States Design Patent** (10) Patent No.: **US D972,647 S**
(45) Date of Patent: **** Dec. 13, 2022**

(54) **SPIKE BATTLE BALL GAME**

(71) Applicant: **Hongyu Wang**, Jian (CN)

(72) Inventor: **Hongyu Wang**, Jian (CN)

(**) Term: **15 Years**

(21) Appl. No.: **29/705,066**

(22) Filed: **Sep. 9, 2019**

(51) LOC (13) Cl. **21-01**

(52) U.S. Cl.
USPC **D21/335; D21/385; D21/302; D21/312; D21/722**

(58) **Field of Classification Search**

USPC ..... D21/722, 723, 811, 385, 397, 466, 301, D21/313, 314, 318, 335, 338, 339, 362, D21/686, 694, 698, 303, 302, 304, 300, D21/334, 336, 341, 342, 343, 319, 789, D21/790, 791, 792, 312, 322, 699, 705; 273/398-404, 343, 317, 336, 348, 407, 273/408, 410, 108, 287, 331, 236, 118 R, 273/123 R, 127 R, 120 R, 127 B, 395, 273/396, 245; 473/431, 434, 180, 175, 473/179, 182, 185, 187, 569, 592; D6/392, 718; 5/110-114, 120-123, 89.1, 5/127-130, 625, 627, 655, 630-634

(57) **CLAIM**

The ornamental design for a spike battle ball game, as shown and described.

DESCRIPTION

FIG. 1 is a perspective view of a spike battle ball game showing my new design;

FIG. 2 is a perspective view of another state thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 8 Drawing Sheets
